UNITED STATES PATENT OFFICE

SAMUEL ROSS, OF NORTH BERGEN, NEW JERSEY

DESIGN FOR A JAR

Application filed August 22, 1929. Serial No. 32,516. Term of patent 7 years.

To all whom it may concern:

Be it known that I, SAMUEL Ross, a citizen of the United States, residing at North Bergen, in the county of Hudson and State of New Jersey, have invented a new, original, and ornamental Design for Jars, of which the following is a specification, reference being had to the accompanying drawing, forming a part thereof.

The figure is a perspective view of a jar showing my new design.

I claim:

The ornamental design for a jar as shown.

SAMUEL ROSS.
